(57) **CLAIM**

The ornamental design for a wall lamp as shown.

DESCRIPTION

FIG. 1 is a front elevational view of a wall lamp showing our new design;

FIG. 2 is a rear elevational view thereof;

FIG. 3 is a top plan view thereof;

FIG. 4 is a bottom plan view thereof;

FIG. 5 is a perspective view thereof;

FIG. 6 is a second perspective view thereof;

FIG. 7 is a third perspective view thereof;

FIG. 8 is a fourth perspective view thereof;

FIG. 9 is a fifth perspective view thereof; and,

FIG. 10 is a sixth perspective view thereof.

1 Claim, 10 Drawing Sheets
